(57) **CLAIM**

The ornamental design for an eyewear viewing device, as shown and described.

DESCRIPTION

FIG. 1 is a front perspective view of the eyewear viewing device in the present invention with the electronic viewer portion being on one side in an upper position and earpiece or earphone speakers being in a lower position.

FIG. 2 is a front view thereof.

FIG. 3 is a rear view thereof.

FIG. 4 is a top view thereof.

FIG. 5 is a bottom view thereof.

FIG. 6 is a left side view thereof.

FIG. 7 is a right side view thereof.

FIG. 8 is a rear perspective view thereof.

FIG. 9 is a front perspective view thereof with the electronic viewer portion in a lower position.

FIG. 10 is a side perspective view thereof with the earphone speakers folded in an up position.

FIG. 11 is a front perspective view thereof with the electronic viewer portion separated from the eyewear portion.

FIG. 12 is an opposite side perspective view thereof converted to have the electronic viewer portion attached to an opposite side of the eyewear portion.

FIG. 13 is a front perspective view thereof with the electronic viewer portion separated from the eyewear portion that is in a folded position; and,

FIG. 14 is a rear perspective view thereof with the electronic viewer portion separated from the eyewear portion that is in a folded position.

The eyewear viewing device in the present invention is an electronic eyewear viewing device including an arm having an electronic viewer portion with a display, removably attachable to an eyewear portion, that can be worn by a user as eyewear, glasses or goggles, and images generated by the eyewear viewing device can be viewed.
